UNITED STATES PATENT OFFICE.

DEAN M. SOLENBERGER, OF CLEVELAND, OHIO, ASSIGNOR TO THE SIMPLEX PISTON RING COMPANY OF AMERICA, INC., A CORPORATION OF OHIO.

DEVICE FOR REDUCING PISTON SLAP IN INTERNAL-COMBUSTION ENGINES.

Original application filed March 1, 1926, Serial No. 91,601, now Patent No. 1,662,544, dated March 13, 1928.
Divided and this application filed September 26, 1927. Serial No. 222,094.

The invention relates to devices for preventing piston slap in internal combustion engines and forms a divisional of part of the subject matter of my former application Ser. 5 No. 91,601, filed March 1, 1926. In this earlier application a number of different specific constructions were shown all including a radially expandable piston ring in a groove in the piston together with means for exerting a 10 preponderance of radial pressure between the ring and one side of the piston whereby said piston is held in closer contact with the opposite side of the cylinder.

The present invention is a construction of 15 this general character in which the piston is provided with an eccentric groove being of greater depth on one side than the other and the invention consists in the novel construction and combination of parts as hereinafter 20 set forth:

In the drawings:

Figure 1 is a horizontal section through an engine cylinder and piston constructed in accordance with my invention.

Figure 2 is a vertical section therethrough.

In the present state of the art piston rings are frequently provided with expanders located between the inner face of the ring and the bottom of the ring groove to increase the 30 radial pressure and to distribute the same about the axis of the cylinder. Such a construction will not always prevent piston slap as the radial pressures on opposite sides are in exact balance and therefore may not under 35 some conditions overcome the alternately opposite angular thrust of the connecting rod. If, however, the clearance between the inner face of the ring and the bottom of the ring groove is greater on one side of the piston 40 than the diametrically opposite side this will cause a preponderance of resilient pressure in the shallow portion of the groove which will tend to hold the piston to one wall of the cylinder.

To produce the construction just described 45 all that is necessary is to deepen the groove on one side of the piston which may be practically accomplished by the use of a suitable grooving tool. The same or similar piston rings and reinforcing expanders are then inserted in the groove with the result that a differential radial pressure is applied to diametrically opposite sides of the ring. This, as previously stated, will cause the piston to travel in closer contact with the cylinder wall 50 on the low pressure side and will thereby lessen piston slap.

In detail A is the piston having the eccentric groove B therein having the greatest depth at the point C and the least depth at the 55 diametrically opposite point C'. B is a trans-split piston ring located in said groove and E is a corrugated ribbon expander inserted between the inner face of the ring and the bottom of the groove. By properly selecting 60 the expander E any desired differential pressure may be placed upon the piston.

What I claim as my invention is:

1. The combination with a cylinder, of a piston loosely fitting the same provided with 70 a ring groove of greater depth on one side of said piston than upon the diametrically opposite side, a trans-split ring engaging said groove and a corrugated ribbon expander located between the inner face of the ring and 75 the bottom of the groove.

2. The combination with a cylinder, of a piston loosely fitting the same provided with an eccentric ring groove having the greater 80 depth on one side of the piston than upon the diametrically opposite side, a trans-split ring of uniform radial depth engaging said groove and a uniformly corrugated ribbon expander located between the inner face of the ring and the bottom of the ring groove.

In testimony whereof I affix my signature.

DEAN M. SOLENBERGER.
